GRINDING WHEEL TRUING APPARATUS

Herbert A. Silven, Worcester, Mass., assignor to
Norton Company, Worcester, Mass., a corpora-
tion of Massachusetts

Application November 21, 1944, Serial No. 564,441

7 Claims. (Cl. 125—11)

This invention relates to grinding machines, and more particularly to a grinding wheel truing apparatus.

One object of the invention is to provide a simple and thoroughly practical truing apparatus for truing the operative face of a grinding wheel. Another object of the invention is to provide a truing apparatus whereby the opposed faces of a pair of spaced grinding wheels may be successively trued. Another object of the invention is to provide an improved mechanism for successively truing the plane operative faces of a pair of opposed grinding wheels with either plane or frusto-conical faces.

Another object of the invention is to provide a truing apparatus having two opposed truing tools arranged for successively truing the operative faces of two opposed grinding wheels, in which the truing tools are maintained in a fixed position for a truing operation so that it is not necessary to reset the wheel positioning mechanism after the truing operation has been performed. Another object of the invention is to provide an adjusting mechanism to facilitate compensation for wear on the truing tools. Other objects will be apparent from the foregoing disclosure.

The invention accordingly consists in the features of construction, combinations of elements, and arrangements of parts, as will be exemplified in the structure to be hereinafter described, and the scope of the application of which will be indicated in the following claims.

In the accompanying drawings in which is shown one of various possible embodiments of the mechanical features of this invention:

Fig. 1 is a front elevation of a hydraulically operated surface grinding machine, illustrating the improved truing apparatus;

Fig. 2 is a fragmentary front elevation, on an enlarged scale, of the improved truing apparatus;

Fig. 3 is a plan view of the truing apparatus on an enlarged scale;

Fig. 4 is a longitudinal sectional view, taken approximately on the line 4—4 of Fig. 3, through the truing apparatus;

Fig. 5 is a cross sectional view, on an enlarged scale, taken approximately on the line 5—5 of Fig. 3, showing the adjusting mechanism for one of the truing tools; and

Fig. 6 is a fragmentary diagrammatic view, showing the relationship of the truing tools and the grinding wheels.

A grinding machine has been illustrated in the

drawings comprising a base 10 which supports a longitudinally movable work table 11 on suitable slideways (not shown). A transversely movable table 12 is supported on slideways formed on the upper surface of the longitudinally movable table 11, said slideways being arranged so that a work piece supported on said transversely movable table may be moved either longitudinally or transversely for a grinding operation. The base 10 is provided with an upwardly extending column 13 which supports a vertically movable grinding wheel slide 14 having suitable slideways formed between the slide 14 and the column 13. The slide 14 serves as a support for a vertically arranged grinding wheel spindle 15 which in turn supports a pair of spaced grinding wheels 16 and 17, the grinding wheels 16 and 17 being arranged successively to grind an upper and a lower surface on a work piece 18. The work piece 18 is provided with a plurality of webbed portions 19 having upper and lower parallel plane surfaces to be ground to a predetermined extent.

Grinding wheel feed

25 The wheel slide 14 is preferably hydraulically controlled by means of a cylinder 20 which is fixedly mounted within the column 13. A slidably mounted piston 21 is provided in the cylinder 20 and is fixedly connected to a double end piston rod 22. The piston rod 22 extends through the end caps formed on the opposed ends of the cylinder 20. The upper end of the piston rod 22 is fixedly connected to a bracket 23 which is in turn fixedly mounted on the vertically movable wheel slide 14.

40 A manually operable control lever 25 is provided for actuating a control valve (not shown) to admit fluid either through a pipe 26 or through a pipe 27 into the cylinder 20 to cause the piston 21 and the wheel slide 14 to move either upwardly or downwardly, depending upon the direction of movement of the control lever 25.

45 The machine is arranged so that the grinding wheels 16 and 17 may be precisely positioned first to grind the upper surfaces of the webs 19 and then to grind the lower surfaces thereon. At the start of a grinding operation the wheel slide 14 is moved downwardly to position the wheel 16 for grinding the upper surfaces of the webs, after which the wheel slide 14 is moved upwardly to position the wheel 17 for grinding the under surfaces of the webs 19. It is desirable to provide a suitable stop mechanism for each of the grinding wheels for precisely determining the up and down positions of the wheel slide 14 so that the

wheels 16 and 17 may be precisely positioned for successive grinding operations.

The piston rod 22 is provided with a feed screw portion 30 which serves as a feed screw. A sleeve 31 is screw threaded onto the feed screw 30. A worm gear 32 is slidably keyed onto the outer periphery of the sleeve 31. The worm gear 32 is held against axial movement and the piston rod 22 and the sleeve 31 are free to move in an axial direction during the hydraulic feeding movement of the wheel slide 14. The worm gear 32 meshes with a worm (not shown) formed on the inner end of a rotatable shaft 33. A manually operable feed wheel 34 is mounted on the outer end of the shaft 33 and is provided with a standard micrometer feed adjusting mechanism 35 which is common and well known in the grinding art. This micrometer adjusting mechanism is substantially the same as that shown in the expired patent to C. H. Norton, No. 762,838 dated June 14, 1904. The feed wheel 34 is provided with a stop abutment (not shown) by means of which the feed wheel may be turned to a predetermined position precisely to adjust the position of the upper wheel 16. Rotation of the feed wheel 34 serves to transmit a rotary motion to the sleeve 31 precisely to position the sleeve 31 relative to the feed screw 30. The lower end of the sleeve 31 is arranged when moved in a downward direction to engage the upper end cap of the cylinder 20 and serves as a positive stop to limit the down feeding movement of the wheel slide 14 precisely to position the wheel 16 relative to the work piece to be ground. To compensate for wear on the grinding wheel 16, it is merely necessary to adjust the hand feed wheel 34 to re-position the stop sleeve 31 so as to allow the wheel slide 14 and grinding wheel 16 to move to a slightly lower position.

A similar feeding mechanism is provided to control the upward feeding movement of the slide 14 and the grinding wheel 17 to position the grinding wheel 17 in a predetermined position relative to the surface of the work piece to be ground. The piston rod 22 is provided with a second feed screw 38. A stop sleeve 39 is threaded onto the feed screw 38. A worm gear 40 surrounds the sleeve 39 and is slidably keyed to the outer peripheral surface thereof. A worm (not shown) formed on the inner end of the shaft 41 meshes with the worm gear 40. A manually operable feed wheel 42 is mounted on the outer end of the shaft 41 and is provided with the usual micrometer adjusting mechanism 43. The micrometer adjusting mechanism 43 is provided with a stop abutment which is arranged to engage a stop (not shown) mounted on the base of the machine for limiting the rotary movement of the feed wheel 42. When the wheel slide and grinding wheel 17 are moved in an upward direction, the feeding movement continues until the upper end of the sleeve 39 engages the end face of the lower cylinder cap which serves as a positive stop to limit the upward feeding movement of the grinding wheel slide 14 precisely to position the operative face of the grinding wheel 17 relative to the lower face of the work piece to be ground. It will be readily apparent from the foregoing disclosure that by adjusting the feed wheel 42, the position of the stop sleeve 39 may be readily adjusted so as to compensate for wear of the grinding wheel 17.

It is desirable that a suitable truing apparatus be provided so that the opposed faces of the

grinding wheels 16 and 17 may be successively trued to the desired and predetermined extent. It is desirable to provide a truing mechanism in which the truing diamonds are fixed during normal operation of the machine so that after the grinding wheels have been trued, it is not necessary to reset the feeding mechanism before resuming the grinding operation. The diamonds are adjustable only to compensate for wear of the diamonds themselves. In the grinding operation illustrated in the present case, it is desirable that the operative faces of the grinding wheels be provided with a slightly back tapered or frusto-conical operative face which tapers toward the wheel spindle in a manner similar to that shown diagrammatically in Fig. 6.

A pair of diamonds or truing tools 50 and 51 are provided to true the operative faces of the grinding wheels 16 and 17, respectively. These diamonds are mounted in a manner to be herein-after described and are arranged to be traversed in a direction such as illustrated by the line 53 (Fig. 6). This line is parallel to the face of the grinding wheel 16 to be trued by the diamond 50 and is also parallel to the face of the grinding wheel 17 to be trued by the diamond 51.

The truing mechanism has been illustrated in Figs. 2 to 6 inclusive. A frame 60 is fastened to the column 13 of the machine. This frame preferably comprises a pair of brackets 61 and 62 which are bolted to the main part 60 of the frame and each of these brackets 61 and 62 is rigidly bolted to opposite side faces of the column 13. A plate 63 is pivotally supported on a stud 64 which is in turn fixedly mounted on the frame 60. The plate 63 may be clamped in adjusted position on the frame 60 by means of clamping screws 65, 65a, 66, 66a and 66b, respectively, formed in the plate 63 and are screw threaded into the frame 60. It will be readily apparent from the foregoing disclosure that the plate 63 which serves as a support for the truing apparatus may be angularly adjusted to determine the path of movement of the truing tools 50 and 51 so that the truing tools may be moved either in a plane normal to the axis of rotation of the grinding wheels 16 and 17 or at an angle thereto, depending upon whether a flat operative face or a tapered operative face is desired.

The plate 63 is provided with a pair of spaced bearing brackets 70 and 71. The bearing bracket 70 rotatably supports one end of a longitudinally extending, rotatably adjustable sleeve 72 (Fig. 4). The sleeve 72 is supported within a concentric sleeve 73 which is journaled in a bearing surface formed in the bracket 71. The sleeve 73 is provided with an adjustably mounted truing tool arm 74 which serves as a support for the truing tool or diamond 50. Similarly, the sleeve 72 is provided with a truing tool arm 75 which serves as a support for the diamond or truing tool 51.

In order to traverse the truing tools 50 and 51 successively across the operative faces of the grinding wheels 16 and 17, respectively, a suitable traversing mechanism is provided comprising a manually operable hand wheel 80 which is mounted on the outer end of a feed screw shaft 81. The feed screw shaft 81 is rotatably supported within the sleeve 72. The feed screw shaft 81 is provided with a threaded portion 82 which meshes with a nut 83. The nut 83 is formed integral with a bracket 84 which is fixedly mounted to the bearing bracket 70. It will be readily apparent from the foregoing disclosure that a rotary motion of the hand wheel 80 will be

transmitted through the feed screw 82 and nut 83 to cause the feed screw shaft 81 together with the sleeves 72 and 73 to traverse longitudinally in an axial direction to traverse the truing tools 50 and 51 across the operative faces of the grinding wheels 16 and 17.

The truing tools 50 and 51 are positioned so that when the grinding wheels 16 and 17 are successively positioned in operative grinding positions, the diamonds may be traversed across the faces thereof to true them as desired. If it is desired to true a thousandth of an inch off the face of the grinding wheel 16, the feeding mechanism, that is, the feed wheel 34, is rotated to adjust the sleeve 31 relative to the feed screw 30 so that the grinding wheel 16 is fed downwardly to a new position, after which the truing tool may be traversed across the face thereof. The trued face of the wheel 16 is then in position so that when grinding is resumed, no re-adjustment of the feed mechanism is necessary to feed the wheel downwardly to grind the surface of the work to the desired and predetermined extent. Similarly, when the lower wheel 17 is trued, the feed wheel 42 may be turned to adjust the sleeve 39 relative to the screw 38 to reposition the grinding wheel 17 for a truing operation.

It is desirable to provide a suitable mechanism normally to hold the sleeves 72 and 73 against rotation and to facilitate adjustment of the truing tools 50 and 51 to compensate for diamond wear. An arm 90 is mounted on the outer end of the sleeve 72. Similarly, an arm 91 is mounted on the outer or right-hand end of the sleeve 73. The arms 90 and 91 are substantially identical in shape and are arranged to facilitate angular adjustment of the sleeves 72 and 73, respectively. Since these arms are identical, only one of them has been illustrated in detail.

The bearing brackets 70 and 71 also serve as supports for a slidably mounted rod 92. The rod 92 extends through elongated rectangularly shaped openings 93 and 94 formed in the arms 90 and 91, respectively. An adjusting screw 95 is screw threaded into a portion 96 in the arm 90. The other end of the screw is rotatably supported in a bearing 97 formed in the arm 90. An adjusting knob 98 is mounted on the outer end of the adjusting screw 95 to facilitate manual adjustment thereof. The screw 95 passes through an aperture 99 formed in the rod 92. A fixed collar 100 is mounted on the screw 95 and bears against a plane surface milled on the side of the rod 92. A thrust collar 101 is slidably mounted on the other end of the screw 95 to facilitate manual adjustment thereof and bears against a plane milled surface on the opposite side of the rod 92. A compression spring 102 is interposed between the thrust collar 101 and the right-hand inner face of the aperture 93 of the arm 90. It will be readily apparent from the foregoing disclosure that a rotary adjustment of the knob 98 will be transmitted angularly to adjust the arm 90 relative to the fixed rod 92 so as to adjust the position of the diamond 51 which trues the lower wheel 17. The knob 98 is provided with graduations 103 and an index mark 104 is fixedly mounted on the arm 90 to facilitate precise adjustment of the diamond 51 in setting up the machine and also to compensate for wear of the diamond 51.

A similar screw (not shown) is provided for adjusting the arm 91 relative to the fixed rod 92. The details of this adjustment have not been illustrated since this mechanism is identical with

that shown in connection with the arm 90 as above described. A graduated knob 105 is mounted on the outer end of the adjusting screw (not shown) for adjusting the arm 91 as desired.

5 When it is desired to true the grinding wheels, the operator adjusts the position of the feed stop control wheels 34 and 42, respectively, by an amount equal to the amount it is desired to true off the faces of the grinding wheels 16 and 17, respectively. After this adjustment has been made, the hand wheel 80 is rotated to traverse the truing tools 50 and 51 relative to the operative faces of the grinding wheels 16 and 17, respectively, successively to true the operative faces thereof. The diamonds or truing tools 50 and 51 are not adjusted during use of the machine except to compensate for wear on the diamonds themselves.

10 The operation of this improved truing apparatus will be readily apparent from the foregoing disclosure. Assuming all the adjustments have been previously made, that is, the frame 63 has been adjusted to the desired angular position to determine the path of travel of the truing tools 50 and 51 so that either a plane radial face may be trued or a tapered face may be trued as desired, the lever 25 is then shifted to cause a downward movement of the piston 21 to position the sleeve 31 against the upper end of the cylinder 20. The feed wheel 34 may then be adjusted to feed the grinding wheel 16 downwardly by an amount equal to that desired to be trued off the face of the grinding wheel 16. The hand wheel 80 may then be rotated to traverse the truing tool 50 across the operative face of the grinding wheel 16 to true the same. During this truing operation, the diamond 51 is out of contact with the grinding wheel 17. After the grinding wheel 16 has been trued to the desired 15 and predetermined extent, the lever 25 is again shifted to cause an upward movement of the piston 21 and the wheel slide 14 to position the stop sleeve 39 against the lower end of the cylinder 20 so as to position the grinding wheel 17 in a predetermined operative position. The feed wheel 42 may then be adjusted to move the wheel 17 upwardly by an amount equal to that desired to be trued off the operative face thereof. After this adjustment has been made, the hand wheel 20 30 may then be rotated to traverse the truing tool 51 across the operative face of the grinding wheel 17 to true the operative face of said wheel. After these truing operations have been completed, the grinding operation may again be resumed without the necessity of re-adjusting the feed mechanisms to compensate for the truing operation.

25 It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

30 1. In a truing apparatus for truing the plane operative face of a grinding wheel, means to locate said wheel in a predetermined grinding position, a truing tool, a non-rotatable slidably-mounted sleeve to support said truing tool, means to traverse said sleeve in an axial direction to

traverse the truing tool across the face of said wheel, and means rotarily to adjust said sleeve to adjust the position of the truing tool so as to compensate for wear thereon.

2. In a truing apparatus for truing the opposed faces of a pair of spaced grinding wheels, means to locate said wheels successively in predetermined grinding positions, a pair of truing tools, a pair of non-rotatable slidably-mounted concentric sleeves each of which is arranged independently to support one of said truing tools, said truing tools being positioned successively to true the operative faces of both of said grinding wheels when the grinding wheels are in a final grinding position, means simultaneously to traverse said sleeves and truing tools, and means rotarily to adjust each of said sleeves independently to adjust the position of said truing tools so as to compensate for wear thereon.

3. In a truing apparatus for truing the opposed faces of a pair of spaced grinding wheels, means including a piston and cylinder to locate said wheels successively in predetermined grinding positions, a pair of truing tools, a pair of slidably-mounted non-rotatable coaxial sleeves each of which is arranged to support one of said truing tools, means including a manually operable rotatable nut and screw mechanism to traverse said sleeves longitudinally so as to traverse the truing tools across the operative faces of said wheels, and independent means angularly to adjust said sleeves so as to adjust the position of said truing tools to compensate for wear thereon.

4. In a truing apparatus for truing the opposed faces of a pair of spaced grinding wheels, means to locate the wheels successively in predetermined positions, a pair of truing tools, a pair of non-rotatable slidably-mounted concentric sleeves each of which is arranged independently to support one of said truing tools, said truing tools being positioned successively to true the operative faces of both of said grinding wheels when the grinding wheels are in a final grinding position, a slidably mounted rod, connections between each of said sleeves and said rod normally to hold said sleeves against rotation, and a micrometer adjusting mechanism associated with said connections to facilitate an independent rotary adjustment of each of said sleeves to adjust the position of said truing tools so as to compensate for wear thereon.

5. In a truing apparatus for truing the opposed faces of a pair of spaced grinding wheels,

means to locate the wheels successively in predetermined grinding positions, a pair of truing tools, a pair of non-rotatable slidably-mounted concentric sleeves each of which is arranged independently to support one of said truing tools, means including a nut and screw mechanism simultaneously to traverse said sleeves and truing tools, a slidably mounted rod, an independent arm on each of said sleeves, and independent connections between each of said arms and said rod normally to hold said sleeves against rotation, said connections including micrometer adjusting screws to facilitate a rotary adjustment of said sleeves to compensate for wear on the truing tools.

6. In a truing apparatus for truing the opposed faces of a pair of spaced grinding wheels, means to locate the wheels successively in predetermined grinding positions, a pair of truing tools, a pair of slidably-mounted non-rotatable coaxial sleeves independently to support each of said truing tools, means to traverse said sleeves simultaneously to traverse the truing tools successively across the operative faces of said wheels, independent means rotarily to adjust said sleeves to adjust the position of said truing tools so as to compensate for wear thereon, and an adjustably mounted frame to support said sleeves to facilitate adjustment of the path of movement of the truing tools so that either a plane or a tapered face may be produced on said wheels.

7. In a truing apparatus for truing the opposed faces of a pair of spaced grinding wheels, means to locate said wheels successively in predetermined grinding positions, a truing apparatus frame, a pair of spaced truing tools, a pair of slidably-mounted non-rotatable coaxial sleeves independently to support each of said truing tools on said frame, means including a nut and screw mechanism to traverse said sleeves simultaneously to traverse said truing tools successively across the operative faces of said wheels, a slidably mounted rod on said frame, independent connections between each of said sleeves and said rod normally to hold said sleeves against rotation, said connections including micrometer adjusting screws to facilitate a rotary adjustment of said sleeves so as to compensate for wear on said truing tools, and means to adjust the position of said frame to facilitate adjustment of the path of movement of the truing tools so that either a plane or a tapered face may be produced on said wheels.

HERBERT A. SILVEN.
